HOLDFAST HAVING SLIDABLE JAW SEQUEN-
TIAILY POSITIONED AND ADVANCED BY
PLURAL-CAM LEVER

Alf Nikolaj Johansson, Bleket, Sweden

Application August 7, 1947, Serial No. 767,135
In Sweden July 15, 1941Section 1, Public Law 690, August 8, 1946
Patent expires July 15, 1961

8 Claims. (Cl. 81—26)

1

The object of the present invention is a holdfast or a vise of the kind having a jaw rigidly attached to a guide or the like and a jaw movable along the guide and adapted to be pressed against the first-mentioned jaw by means of a lever provided with an eccentric or the like. The holdfast according to the invention is particularly characterized in that the movable jaw is arranged on a sliding block movable along the guide and adapted to be clamped by means of the lever, the sliding block grasping the guide by means of legs which are elastic relatively to each other and project into a hole of the lever having such a shape that the legs are moved in a direction against each other and are clamped against the guide when the lever is swung from a position in which the sliding block slides freely on the guide, the lever being adapted upon said clamping and when being further swung, to press the movable jaw against the stationary jaw by means of the eccentric.

The invention is illustrated in the accompanying drawings. Fig. 1 is a front view of a holdfast arranged in accordance with the invention. Fig. 2 is a sectional view on the line 2—2 of Fig. 1. Figs. 3 and 4 are sectional views on the line 3—3 of Fig. 2 and show the movable jaw, the sliding block and the lever of the holdfast, in two different positions. Fig. 5 is a partly sectional elevation on the line 5—5 of Fig. 6 and shows a modification of the invention. Fig. 6 is a plan view of the holdfast in Fig. 5. Fig. 7 is a sectional view along the line 7—7 in Fig. 5 showing the sliding block of the holdfast in Figs. 5 and 6. Figs. 8 and 9 illustrate another modification of the invention, Fig. 8 showing a section on the line 8—8 of Fig. 9, and Fig. 9 is a partly sectional view on the line 9—9 of Fig. 8.

In the drawing, Figs. 1 to 4, 2 indicates the one jaw of the holdfast, which jaw forms the under piece of a frame, which frame, moreover, consists of an upper piece 1 and two side-posts 3. A tubular guide 4 having a longitudinal groove 5 is attached at its ends to the jaw 2 and the upper piece 1. The jaw 2 is formed in a manner such that wooden laths 15 or the like to be glued together can be placed thereon and be held edge to edge by abutting against the posts 3.

A movable jaw 14 is placed on a sliding block 10 movable along the guide 4 and liable to be clamped by means of a lever 8, the sliding block grasping the guide by means of legs 11 which are elastic relatively to each other and are rigidly connected with the sliding block 10. The sliding block 10 is cylindrical and has a hole for the

2

guide 4, which hole is placed at right angles to the cylinder axis. Turning movement of the block 10 around the guide 4 is prevented by a bolt 5a engaging the groove 5. On the sliding block 10 is fastened a cylindrical pin and this pin as well as the block 10 are slotted from the hole for the guide 4 to the end of the pin, the elastic parts or legs 11 being thus formed. Therefore, the legs 11 are semi-circular or the like and are situated one on each side of the slot, and for the purpose of clamping the sliding block on the guide the legs may be pressed together by means of the lever 8 which is journalled about the slotted pin by means of an oval hole. When the lever 8 is swung in the one or the other direction, the slot is closed (Fig. 4) and the sliding block is clamped around the guide.

When clamping in this way by swinging the lever through a certain angle an eccentric cam 9 of the lever will engage the movable jaw 14 and when the lever is further swung, the jaw 14 is pressed against the articles placed on the jaw 2. When the lever is swung in the opposite direction the jaw 14 is first loosened and then the sliding block 10, the legs 11 of which automatically spring outwards. If swinging is continued in the same direction the sliding block will again be clamped and the jaw 14 will be pressed against the articles by means of another eccentric cam 9. Thus, it is possible to swing the lever 8 in either direction for pressing the jaw 14 against the articles to be glued. The jaw 14 is suspended on the legs 11 in such a manner that it may move sufficiently for effecting the pressing after the sliding block 10 has been clamped to the guide 4. The jaw 14 is retained by means of a key against which it abuts by the aid of a washer 13. A key 7 and a nut 6 retain the guide in the upper piece 1 and the jaw 2 respectively.

In Figs. 5 to 7, 16 indicates the one jaw of the holdfast, which jaw is rigidly attached to a guide 17 which consists of a cylindrical bar. The other jaw 18 of the holdfast is movable along the guide 17 and has an elongated member 19 having a substantially rectangular hole 20 through which passes the guide 17. In the hole 20 is disposed a sliding block 21 the length of which is smaller than the length of the hole so that the sliding block is movable relatively to the jaw 18 in the direction of the guide. The breadth of the sliding block is slightly less than the breadth of the hole 20. The sliding block 21 has a hole 22 so that it forms a sleeve which cooperates with the guide 17. The block or sleeve 21 is longitudinally split from the upper surface of the

hole to the upper surface of the block so that the split portions can be pressed against the guide by means of two legs 23, corresponding to legs 11 in Figs. 1-4.

Around the legs 23 is journalled a hub 24 of a lever 25. A hole 26 in the hub 24 is eccentric relatively to the outer cylindrical face of the hub and is disposed in such a manner, that, in the position of the lever shown in Figs. 5 and 6, the distance between the hole 26 and a face 27 of the jaw 18 is a minimum. The lever is in this position parallel with the guide 17, and by swinging the lever to the right or left the outer cylindrical face of the hub 24 will be pressed against the face 27 of the jaw 18 so that the jaw is moved against the fixed jaw 16.

The legs 23 have cylindrical outer surfaces which are concentric when the legs are unstrained. Around the legs there is a groove 28 in which extends the rounded end of the lever 25 which is threaded and inserted in a threaded hole 29 in the hub 24. The cross section of the groove 28 is adapted to the rounding of the end of the lever. From Fig. 7 it will be obvious that the groove 28 has a recess 30 which is arranged to receive the end of the lever 25 when the lever is in the shown position.

By swinging the lever 25 from the aforesaid position the end of the lever will be pressed against the shallow part of the groove 28 and thus cause the legs 23 to move against each other whereby the slot between the legs is closed more or less and the sliding block is clamped around the guide. In consequence of the eccentric disposal of the hole 26 for the legs 23 the cylindrical outer face of the hub 24 at the same time is pressed against the face 27 so that the jaw 18 is moved against the jaw 16. During the first portion of the swinging movement of the lever 25, the block portions will be firmly clamped to the guide 17, while the jaw 18 is slightly pressed against an article between the jaws 16 and 18. Thereupon, further swinging of the lever causes the jaw 18 to be firmly pressed against the article.

It is evident that, by screwing the lever in the hub 24 to the right or left, the end of the lever can be brought in every desired radial position relatively to the groove 28, so as to vary the clamping force exerted by the legs on the guide.

The lever-bar 25 is fixed to the hub by means of a stop-nut 31 which is arranged to be pressed against the hub.

In the device shown in Figs. 5 to 7 the lever may be immovably attached to the hub, while a separate screw may be arranged to engage the legs 23. The screw may for example be disposed in the hub opposite the lever 25. It is not necessary that the outer cam-face of the hub be cylindrical but it can have any desired form, for instance the face may be formed in such a manner that the length of movement of the jaw 18 will be shorter by swinging the lever in one direction than in the other direction from the position shown in the drawing. An embodiment including such modifications is illustrated in Figs. 8 and 9. In this instance the handle 25a of the lever is integral with the hub portion 24a. The non-circular portions of the legs 23a of the block are engaged by an abutting member 32 inserted into a recess 33 in the portion 24a. An adjustable screw 34 threaded into a radial bore in the portion 24a maintains the member 32 in desired radial position. In the

present embodiment, the cam face 35 of the lever has a greater radius of curvature than the cam face 36, with the result that the lever when swung in a clockwise direction as viewed in Fig. 9 will engage the face 27a of the movable jaw 18a and move said jaw more rapidly than in the case when the lever is swung in an anti-clockwise direction. It will be evident that in the latter case a smaller force has to be applied to the lever to exert a given pressure upon the jaw 18a. It will further be evident that the purpose of the member 32 is the same as that of the inner end of the handle 25 according to Figs. 5 and 6.

It is obvious that the specific surface pressure between the co-operating faces should be as small as possible. The form and dimensions of the faces therefore ought to be adapted to the loads, for which the holdfast is intended.

What I claim is:

1. A holdfast comprising a stationary jaw, a guide rigidly attached to said jaw, a jaw movable along said guide, a lever adapted to press said movable jaw toward said stationary jaw, said lever having a pivot aperture and a cam spaced from said aperture and eccentric thereto, a block slidably mounted on said guide, and means to clamp said block to said guide by pivotal movement of said lever, said means comprising spaced resilient block portions having legs projecting into the lever aperture to pivotally mount the lever, and cooperating means on said lever and legs to move the legs toward each other and thereby clamp the resilient block portions against said guide when the lever is swung from its inoperative position in which the block slides freely on the guide, the cam on said lever, upon said lever being further swung, pressing the movable jaw toward the stationary jaw.

2. A holdfast comprising a stationary jaw, a guide rigidly attached to said jaw, a jaw movable along said guide, a lever adapted to press said movable jaw toward said stationary jaw, said lever having a pivot aperture and a cam spaced from said aperture and eccentric thereto, a block slidably mounted on said guide, and means to clamp said block to said guide by pivotal movement of said lever, said means comprising spaced resilient block portions having legs which are substantially semi-circular in cross-section and project into the lever aperture to pivotally mount the lever, and cooperating faces on said lever and legs to move the legs toward each other and thereby clamp the resilient block portions against said guide when the lever is swung in either direction from its inoperative position in which the block slides freely on the guide, the cam on said lever, upon said lever being further swung in the same direction, pressing the movable jaw toward the stationary jaw.

3. A holdfast comprising a stationary jaw, a guide rigidly attached to said jaw, a jaw movable along said guide, a lever adapted to press said movable jaw toward said stationary jaw, said lever having a pivot aperture and two cams spaced from said aperture and eccentric thereto, a block slidably mounted on said guide, and means to clamp said block to said guide by pivotal movement of said lever, said means comprising spaced resilient block portions having legs which are substantially semi-circular in cross-section and project into the lever aperture to pivotally mount the lever, and cooperating faces on said lever and legs to move the legs toward each other and thereby clamp the resilient block portions against

said guide when the lever is swung in either direction from its inoperative position in which the block slides freely on the guide, one of said cams on said lever, upon said lever being further swung in the same direction, pressing the movable jaw toward the stationary jaw.

4. A holdfast comprising a stationary jaw, a guide rigidly attached to said jaw, a jaw movable along said guide, a lever adapted to press said movable jaw toward said stationary jaw, said lever having a pivot aperture and a cam spaced from said aperture and eccentric thereto, a block slidably on said guide together with the movable jaw and with the possibility of a slight movement on the guide relative to the movable jaw, and means to clamp said block to said guide by pivotal movement of said lever, said means comprising spaced resilient block portions having legs projecting into the lever aperture to pivotally mount the lever, and cooperating means on said lever and legs to move the legs toward each other and thereby clamp the resilient block portions against said guide when the lever is swung from its inoperative position in which the block slides freely on the guide, the cam on said lever, upon said lever being further swung, pressing the movable jaw toward the stationary jaw.

5. A holdfast comprising a stationary jaw, a guide rigidly attached to said jaw, a jaw movable along said guide, a lever adapted to press said movable jaw toward said stationary jaw, said lever having a pivot aperture and a member extending into and radially adjustable relative to said aperture, a cam integral with said lever and spaced from said aperture and eccentric thereto, a block slidably mounted on said guide, and means to clamp said block to said guide by pivotal movement of said lever, said means comprising spaced resilient block portions having legs projecting into the lever aperture to pivotally mount the lever, and means on said legs cooperating with said member to move the legs toward each other and thereby clamp the resilient block portions against said guide when the lever is swung from its inoperative position in which the block slides freely on the guide, the cam on said lever, upon said lever being further swung, pressing the movable jaw toward the stationary jaw.

6. A holdfast comprising a stationary jaw, a guide rigidly attached to said jaw, a jaw movable along said guide, a lever adapted to press said movable jaw toward said stationary jaw, said lever having a pivot aperture and a member extending into and radially adjustable relative to said aperture, a cam integral with said lever and spaced from said aperture and eccentric thereto, a block slidably mounted on said guide, and means to clamp said block to said guide by pivotal movement of said lever, said means comprising spaced resilient block portions having legs projecting into the lever aperture to pivotally mount the lever, said legs having recessed portions eccentric to said aperture and cooperating with said member to move the legs toward each other and thereby clamp the resilient block portions against said guide when the lever is swung from its inoperative

position in which the block slides freely on the guide, the cam on said lever, upon said lever being further swung, pressing the movable jaw toward the stationary jaw.

5. A holdfast comprising a stationary jaw, a guide rigidly attached to said jaw, a jaw movable along said guide, a lever adapted to press said movable jaw toward said stationary jaw, said lever including a hub portion having a pivot aperture and a cam spaced from said aperture and eccentric thereto, and said lever including a handle extending radially through said hub portion into said aperture, a block slidably mounted on said guide, and means to clamp said block to said guide by pivotal movement of said lever, said means comprising spaced resilient block portions having legs projecting into the lever aperture to pivotally mount the lever, said legs having recessed portions eccentric to said aperture and cooperating with the inner end of said lever to move the legs toward each other and thereby clamp the resilient block portions against said guide when the lever is swung from its inoperative position in which the block slides freely on the guide, the cam on said lever, upon said lever being further swung, pressing the movable jaw toward the stationary jaw.

8. A holdfast comprising a stationary jaw, a guide rigidly attached to said jaw, a jaw movable along said guide, a lever adapted to press said movable jaw toward said stationary jaw; said lever having a pivot aperture, a cam spaced from said aperture and eccentric thereto, and a threaded radial bore opening into said aperture; a screw in said bore, a block slidably mounted on said guide, and means to clamp said block to said guide by pivotal movement of said lever, said means comprising spaced resilient block portions having legs projecting into the lever aperture to pivotally mount the lever, the outer faces of said legs being non-circular in cross-section, and a member inserted between the inner end of said screw and said legs to move the legs toward each other and thereby clamp the resilient block portions against said guide when the lever is swung from its inoperative position in which the block slides freely on the guide, the cam on said lever, upon said lever being further swung, pressing the movable jaw toward the stationary jaw.
